[57] ABSTRACT

A razor blade assembly comprising razor blade means clamped between a platform member and a cap member. The platform and cap members are provided with dowel and aperture means by which they are connected together with the blade means held therebetween in assembled relationship, the dowels extending through holes in the blade means and the aforementioned aperture means and then expanded whereby to connect the assembly components together. The platform and cap members are further provided with runner means slidably engageable with complementarily shaped rail means of a razor handle.

RAZOR BLADE ASSEMBLY

BACKGROUND OF THE INVENTION

1. Field of the Invention

This invention relates to safety razors and is directed more particularly to a razor blade assembly comprising blade means clamped between two supporting members.

2. Description of the Prior Art

Many safety razors in use today include a head portion which comprises a platform for receiving a blade member, and a cap or pair of cap members for holding the blade member securely against the platform.

Recently, there have evolved razor head units having blade means and head means as one unit which may have a handle molded thereto or which may be adapted for connection to a separate handle means. For example, U. S. Pat. No. 3,488,764, issued Jan. 6, 1970 discloses blade means molded into a disposable unit which may constitute either a razor head or a complete razor.

SUMMARY OF THE INVENTION

An object of the present invention is to provide a razor head unit similar to that disclosed in the above-mentioned patent, but in which the blade means is supported by a platform member and a cap member.

With the above and other objects in view, as will hereinafter appear, a feature of the present invention is the provision of a razor blade assembly including a platform member having ramp means for supporting razor blade means thereon, planar razor blade means disposed on the ramp means, and a cap member connected in rivet-like fashion to the platform member with the blade means disposed therebetween, the rivet means extending through holes in the blade means. The platform and cap members are further provided with runner means adapted to slidably receive a complementarily shaped portion of a razor handle.

The above and other features of the invention, including various novel details of construction and combinations of parts, will now be more particularly described with reference to the accompanying drawings and pointed out in the claims. It will be understood that the particular device embodying the invention is shown by way of illustration only and not as a limitation of the invention. The principles and features of this invention may be employed in various and numerous embodiments without departing from the scope of the invention.

BRIEF DESCRIPTION OF THE DRAWINGS

Reference is made to the accompanying drawings in which is shown an illustrative embodiment of the invention from which its novel features and advantages will be apparent.

FIG. 1 is an exploded perspective view of one form of razor assembly illustrative of an embodiment of the invention;

FIG. 2 is a top plan view;

FIG. 3 is a bottom plan view; and

FIG. 4 is a sectional view taken along line IV-IV of FIG. 2.

DESCRIPTION OF THE PREFERRED EMBODIMENT

Referring to the drawings, it will be seen that the illustrative assembly includes a platform member 2, blade means 4, and a cap member 6.

The platform member 2 includes end walls 8, 10 interconnected by a front wall 12 and a ramp 14. The ramp 14 includes an elongated recess 16 disposed centrally thereof and extending throughout the length of the ramp. The recess 16 of the ramp 14 is provided with a series of holes 18 for receiving cap member projection means, as will be described in detail below. The end walls 8, 10 extend forwardly, or to the right as viewed in FIGS. 1 and 4, and support a guard member 20 which extends the length of the platform member and is spaced from the front wall 12 and the platform 14. Bridge members 22 further interconnect the guard member 20 and the front wall 12. A depending wall 24 (best seen in FIGS. 1 and 4) forms an extension of the front wall 12 and has on its free end a flange 26, the wall 24 and flange 26 forming in conjunction with the end walls 8, 10, a groove 28 which is suited to receive a runner means disposed on a razor handle of the type disclosed, for example, in U. S. patent application Ser. No. 124,216, filed Mar. 15, 1971. The wall 24 may be provided with a notch 29 to facilitate positioning of the blade assembly on the razor handle (FIG. 3). Preferably, the entire platform member, including platform, walls and guard member comprise a unitary member molded of plastic material.

The blade means 4 comprises at least one planar blade member 30 having a cutting edge 32 and a series of holes 34 arranged complementarily with respect to the holes 18 of the platform member 2.

The cap member 6 includes end walls 40, 42, interconnected by a clamp portion 44. The clamp portion 44 includes a clamp surface 46 having an elongated recess 48 from which extend a series of pins 50. The pins 50 are arranged and dimensioned complementarily to the blade means holes 34 and the platform member holes 18. Extending from the clamp portion 44 is a depending wall 52 having on its free end an inwardly extending flange 54. The wall 52 and flange 54 form a groove 56 which is opposed to the above-described groove 28 and which, in conjunction with the groove 28, is adapted to receive the runner means of the razor handle referred to above. Preferably, the cap member comprises a unitary member molded of plastic.

Referring primarily to FIG. 1, it will be seen that in assembly of the unit, the blade means 4 is placed upon the ramp 14 of the platform 2 with the blade means holes 34 in alignment with the platform holes 18. The cap member 6 is then placed upon the blade means with the pins 50 extending through the holes 34, 18, as shown in FIG. 4. The free ends 58 of the pins 50 are then expanded rivet-fashion (not shown) to lock the components together, whereby to permanently secure the blade means between the platform and cap members 2, 6. The blade assembly is then ready for connection to a handle, of the type above referred to, for shaving operations.

It is to be understood that the present invention is by no means limited to the particular construction herein disclosed and/or shown in the drawings, but also com-

prises any modifications or equivalents within the scope of the disclosure.

Having thus described my invention what I claim as new and desire to secure by Letters Patent of the United States is:

1. Razor blade assembly comprising a platform member having first and second end walls interconnected by a front wall and ramp means, a guard portion extending from the first end wall to the second end wall and spaced from said front wall, a first depending wall extending the transverse length of said razor blade assembly at the front of said platform member and having at its free end an inwardly directed first flange means forming a first elongated groove for cooperatively receiving first runner means of a handle, planar blade means disposed on said platform member and having cutting edge means extending outwardly beyond said front wall but short of said guard portion, a cap member having third and fourth end walls interconnected by a clamp portion having a clamp surface in engagement with said blade means, and a second depending wall extending the transverse length of said razor blade assembly at the rear of said platform member and having at its free end an inwardly directed second flange means opposed to said first flange means and forming a second elongated groove for cooperatively receiving runner means of a handle.

2. Razor blade assembly comprising a platform member having a ramp portion, razor blade means disposed on said ramp portion, said razor blade means having a hole therethrough, and a cap member disposed on said blade means, said cap and platform members having pin and hole means in alignment with said blade means hole, said pin means extending through said blade means hole and said hole means and expanded to effect joinder of said platform member and said cap member with said blade means disposed therebetween, said platform member including a first elongated groove for slidably receiving runner means of a handle and said cap member including a second elongated groove opposed to said first groove for cooperatively receiving runner means of said handle.

3. The invention according to claim 1 in which at least one of said grooves is provided with notch means to facilitate positioning of the blade assembly on said handle.

4. The invention according to claim 1 in which said platform member is a molded plastic unitary member and said cap member is molded plastic unitary member.

5. The invention according to claim 1 in which said

razor blade means comprises at least one planar razor blade.

6. Razor blade assembly comprising a platform member having first and second end walls interconnected by a front wall and ramp means, a guard portion extending from the first end wall to the second end wall and spaced from said front wall, a first depending wall extending from said front wall and having at its free end inwardly directed first flange means forming a first groove for slidably receiving first runner means of a handle, planar blade means disposed on said ramp means and having cutting edge means extending outwardly beyond said front wall but short of said guard portion, said blade means having a plurality of holes therethrough, a cap member having third and fourth end walls interconnected by a clamp portion having a clamp surface for engagement with said blade means, a second depending wall extending from said clamp portion and having at its free end inwardly directed second flange means forming a second groove for slidably receiving second runner means of said handle, and pin and hole means provided on said platform and cap members, said pin means extending through said blade means holes, and through said hole means, the free ends of said pin means being enlarged to join together said platform member and said cap member with said blade means disposed therebetween.

7. Razor blade assembly comprising a platform member having first and second end walls interconnected by a front wall and ramp means, a guard portion extending from the first end wall to the second end wall and spaced from said front wall, a first depending wall extending from said front wall and having at its free end an inwardly directed first flange means forming a first groove for slidably receiving first runner means of a handle, planar blade means disposed on said ramp means and having cutting edge means extending outwardly beyond said front wall but short of said guard portion, a cap member having third and fourth end walls interconnected by a clamp portion having a clamp surface in engagement with said blade means, and a second depending wall extending from said clamp portion and having at its free end an inwardly directed second flange means opposed to said first flange means and forming a second groove for slidably receiving second runner means of said handle.

8. The invention according to claim 7 in which at least one of said grooves is provided with notch means cooperative with said handle for positioning of the blade assembly on said handle.
